UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,306,299.

Specification of Letters Patent. Patented June 10, 1919.

Application filed December 27, 1918. Serial No. 268,484.

To all whom it may concern:

Be it known that I, JOHN H. BELL, a citizen of the United States, residing at South Orange, in the county of Essex, State of New Jersey, have invented certain new and useful Improvements in Telegraph Systems, of which the following is a full, clear, concise, and exact description.

This invention relates to telegraph systems and more particularly to duplex or similarly balanced electrical circuits.

The principal object of this invention is to provide an improved organization of apparatus for indicating variation of electrical characteristics in the circuits of duplex telegraph systems or equipments wherein it may be required to maintain predetermined conditions of electrical balance between a plurality of circuits.

In carrying out the present invention, there is provided electroresponsive switching means, current indicating means, and retarded circuit control means coöordinated with duplex circuits in such a manner that any unbalance of the circuits will be indicated before such error may develop sufficiently to interfere with regular signaling operations.

This invention is illustrated diagrammatically in the accompanying drawing, in which, for the sake of clearness only so much of a telegraphic or signaling equipment has been shown as will be necessary to a clear understanding of the invention.

Referring to the drawing, reference character 1 indicates a telegraph transmitter which may be of any well-known form of pole changer or multiplex distributor arrangement, while resistance units 2 and 3 serve as the ratio arms of a bridge duplex respectively formed through an artificial line AL and a main line L. For the reception of signaling impulses which may originate at a distant station on the line L, a circuit is provided through a slow operating relay 5 and a polar relay 7, it being understood that the contacts of the polar relay may be arranged to control a receiving sounder or other suitable devices on which

an incoming message is to be reproduced. As well understood in connection with duplex circuits, changes of current polarity set up by the transmitter 1, although non-effective in the local receiving circuit formed by the relays 5 and 7, due to a balanced condi-

tion of the artificial line AL and the real line L, will, however, control a suitable receiving equipment at a distance station (not shown) on the line L. Conversely, impulses originating at such distant station will cause the operation of polar relay 7.

Referring now more particularly to the features of the present invention, a resistance unit 10 which for convenience, should be of an adjustable type, is connected in a leak circuit which extends from the apex or outgoing connective point of the bridge duplex through the windings of two polar relays 11 and 15, to earth. Under the control of these polar relays is connected an ammeter 21 in such a manner that a current path may be traced therethrough from the line L by way of normal contacts 6 of the relay 5, contact 16 of the relay 15, an impedance unit 20 which may also be of an adjustable type, the windings 22 and 23 of the ammeter 21, and contacts 12 of the relay 11 to the artificial line AL. The position in which the apparatus is shown in the drawing may be understood as corresponding with a period during which an impulse is arriving from the line L while an outgoing impulse is being transmitted by the transmitter 1. Relays 11 and 15, as indicated by the conventional plus and minus signs in the drawing, close contacts 12 and 16 respectively under the influence of an impulse of positive current from the transmitter 1, while a negative impulse from this transmitter will cause the armatures of these relays to close contacts 13 and 17. Therefore, at the instant a negative impulse is sent from the transmitter 1, a circuit may be traced from the real line L by way of the contacts 6 of the relay 5, the contacts 13 of the relay 11, thence through the operating windings of the indicator or ammeter 21, impedance 20 and the contacts 17 of the polar relay 15, to the artificial line.

The contacts of the relays 11 and 15 are so connected together and to ammeter 21 that any currents from the transmitter 1 which may stray between the real line L and the artificial line AL, due to inexactness of balance, will be so routed with respect to their direction through this meter that the needle or indicator 24 thereof will be deflected in the same direction irrespective of the polarity of such stray currents. It will be noted that the ammeter 21 is of the so-called "double throw" type wherein

the needle may move either to the right or to the left-hand side of a central zero point. Therefore, when the nature of the unbalance is such that the artificial line is of higher 5 impedance than the real line, stray currents will flow from the artificial line to the real line and the needle 24 of the ammeter will accordingly be deflected in one direction, while for an inverse condition of unbalance, 10 in which stray currents have a tendency to flow from the real to the artificial line, the needle of the ammeter will be deflected in the opposite direction. It will therefore be clear that in addition to indicating the 15 degree of unbalance, the ammeter 21 will also indicate the direction of such unbalance, thereby definitely indicating the direction of the adjustment which should be made in the artificial line devices.

20 Referring more particularly to the purpose of the relay 5, this slow acting relay should be of such proportions or adjustment that although it will not respond to incoming impulses from a distant station to 25 separate its contacts 6, it will, however, respond to what may be termed a steady current caused, for example, by an idle condition of the transmitting devices at a distant station. Therefore, when signaling impulses 30 are coming in over the line L, this relay will not operate. A prolonged impulse of steady current condition will, however, cause relay 5 to open its contact 6. By this arrangement it will be clear that the circuit 35 of the ammeter 21 is closed only when signaling impulses are arriving from a distant station but is opened automatically by the relay 5 if a prolonged impulse occurs.

As well understood in the art, the artificial 40 line AL may be formed of resistance, inductance and capacity arranged to permit of any desired adjustments of their respective values. Therefore, in case the ammeter 21 indicates the presence of current 45 the adjustable devices of the artificial line may be changed to such point or points that the needle 24 will not be affected but return to its zero position, thereby indicating that the adjustments made have reestablished a 50 balanced condition between the artificial line AL and the real line L. Such adjustment of balance may be carried out and all determinations relative thereto may be reached without in any way interrupting or 55 interfering with any messages which may be under transmission over the line L.

Long line circuits, particularly of the open wire type, are subject to variations in resistance and capacity due ordinarily to

change in the weather as from dry to wet 60 conditions of the atmosphere, and in order to maintain a balanced condition of duplex circuits, it is necessary for the telegraph attendants to vary the adjustment of the devices of the artificial line from time to time. 65 The present arrangement provides that small or incipient variations of unbalance may be immediately indicated, thereby permitting the necessary adjustments to be made in the artificial line before the degree 70 of unbalance reaches a point at which the telegraphic originals would be interfered with, or before the unbalance condition causes entire failure of the telegraphic receiving devices. 75

What is claimed is:

1. In a duplex telegraph system, a real line and an artificial line, transmitting and receiving means included with said real and artificial lines, current indicating means, pole changing means responsive to said transmitting means for controlling said current indicating means, and slow acting electroresponsive means included with said receiving means and controlling the connection of said current indicating means to said real and artificial lines. 80

2. In a duplex telegraph system, a real line and an artificial line, means included with said line for the reception of impulses 90 incoming from said real line, transmitting means included with said lines for sending impulses over said real line, an ammeter, a slow acting relay responsive to said incoming impulses, electroresponsive switching 95 means for reversing connections through said ammeter, and means controlled by said slow acting relay to control the connection of said ammeter to said real and artificial lines. 100

3. In a system of duplex circuits, a real line, an artificial line, means for the reception of impulses from said real line, means for the transmission of impulses to said real line, current indicating means connected intermediate said real line and said artificial line, pole changer means controlled by said transmitter for controlling the connections through said current indicating means, and slow acting electroresponsive switching 110 means included with said real line and said artificial line and responsive to a prolonged impulse from said real line to disable said current indicating means. 105

In witness whereof, I hereunto subscribe 115 my name this 23rd day of December A. D., 1918.

JOHN H. BELL.
